(57) **CLAIM**

The ornamental design for a wireless phone set, as shown and described.

DESCRIPTION

FIG. 1 is a perspective view of wireless phone set showing my new design.

FIG. 2 is a front view thereof.

FIG. 3 is a rear view thereof, wherein the broken lines represent a slot on top of the phone and a phone inlet at the phone base that the broken lines are for illustrative purposes only and form no part of the claimed design.

FIG. 4 is a right view thereof, wherein the broken lines represent the phone inlet at the phone base that the broken lines are for illustrative purposes only and form no part of the claimed design.

FIG. 5 is a left view thereof, wherein the broken lines represent the phone inlet at the phone base that the broken lines are for illustrative purposes only and form no part of the claimed design; and,

FIG. 6 is a top perspective view thereof.

The broken line showing of the wireless phone set is included for the purpose of illustrating portions of the article and forms no part of the claimed design.
